CONTINUE PROCESS AND APPARATUS

August Hartmann, Berlin-Lichterfelde, Walter Hoefinghoff, Hohenlimburg Obernahmer, and Gotthard Bauriedel and Walter Ostermann, Wuppertal-Barmen, Germany, assignors to American Bemberg Corporation, New York, N. Y., a corporation of Delaware

Application January 6, 1933, Serial No. 650,512
In Austria March 5, 1932

12 Claims. (Cl. 18-8)

This invention relates to an improved process of and apparatus for the manufacture of artificial silk and analogous products.

In the treatment of artificial silk thread many methods and apparatus have been devised to subject the thread to various treating liquids and drying mediums without injury thereto. Suggestions have been made to guide artificial filaments in a helical path over discs and the like which partially or entirely dip into treating baths. It has also been suggested that the artificial filaments be guided over rotating reels so constructed as to advance the filaments in an axial direction while spraying the filaments with the desired treating liquid.

One object of this invention is to provide an improved process for the after treatment of artificial silk, wherein a plurality of groups of artificial filaments are advanced together substantially in a helical path over the surface of a rotating cylinder.

Another object of this invention is to provide an improved process of and apparatus for the after treatment of artificial silk filaments whereby an equal and uniform treatment of the filaments may be had.

A further object of this invention is to provide an improved arrangement for the handling of artificial silk filaments whereby the treating liquids will be sprayed on or contacted with the filaments travelling in a substantially helical path.

These and other objects of our present invention will become more apparent from a study of the following description and by reference to the attached drawings in which:

Figure 1 shows a vertically positioned cylinder provided with a suitable source of liquid which directs the liquid tangentially against the cylinder;

Figure 2 is a view in side elevation of a pair of horizontally disposed rollers provided with means for supplying compressed air thereto;

Figure 3 is an end elevation thereof;

Figure 4 is a top plan view thereof;

Figure 5 is a top plan view of the lower roller showing the arrangement for supplying the treating liquids and the compressed air;

Figure 6 is a side elevation of a modified form of treating apparatus;

Figure 7 is an end elevation thereof;

Figure 8 is a top plan view thereof;

Figure 9 is a top plan view of the lower roller showing the wiping arrangement;

Figure 10 is a detailed view of one of the wipers;

Figure 11 is a side elevation of still another modified form of the invention;

Figure 12 is an end elevation thereof; and

Figure 13 is a view showing a roller in a slanting position and provided with a spray device.

Referring now to the drawings and more particularly to Figure 1, there is shown a vertically positioned roller 1, supported by a shaft 2 journaled in the bearing 3. The liquid is sprayed on the roller tangentially thereto by means of a supply pipe 5 located adjacent the top of the roller. The liquid moves downwardly on the roller in a steeper and steeper path gradually increasing in width and drips from the edge 4 of the roller into a ring shaped vat or receiver 6. As will be noted this receiver is provided with a pipe 21 to draw off the used treating liquids. The filament 22 moves along the surface of the roller in a helical path and the different windings are maintained at a uniform distance from each other, by the bar 23 carrying hooks 24 over which each winding is passed.

In Figures 2-5 inclusive, there is shown a modified form of apparatus in which a pair of cylindrical rollers 25 and 26 are provided for the advance of the thread. The liquid supplied by the pipe lines 27 and 28 to the surface of the lower roller 26 has a tendency, because of the gravitational force exerted thereon, to flow downwardly. This tendency is overcome by the use of compressed air supplied through the pipe 29 which will force the liquid along the surface of the roller in an axial direction. The resultant of the movements of the liquids causes the liquid to flow in a substantially helical path.

In accordance with the modification disclosed in Figures 6-10 inclusive, two wiping blades or members 30 and 30' are arranged between the upper and lower rollers 31 and 32 and adjacent the said lower roller, and in a slanting position with respect thereto. The wiping edge of each blade is provided with a plurality of openings or teeth 33. Two different liquids are fed upon the lower rollers by pipe lines 34 and 35. Because of the slanting position of the blades with respect to the lower roller, the liquids will be moved toward the right hand edge of the roller upon the rotation of the said roller in the direction of the arrow "a".

An additional blade 36 positioned between the blades 30 and 30' serves to prevent the commingling of the treating liquids used. In operation the liquids are gradually moved along the surface of the roller passing through the teeth formed in the blades: the liquid will flow through

one of the openings in the blade and is again taken up and advanced through the next opening after a renewed dispersion on the rollers.

In Figures 11 and 12, there is shown a pair of 5 cylinders 37 and 38 provided with a plurality of helical grooves 39. The treating liquids are supplied to the cylinder 38 through pipe lines 40 and 41. Because of the helical grooves the liquid is advanced from one end of the cylinder 38 10 to the other, in this instance from left to right due to the rotation of the cylinders as indicated by the arrow "b". A change in the direction of rotation of the cylinders, or a change of the helical paths of the grooves, will, naturally, result in a 15 change of direction of the advance of the liquids.

In Figure 13, there is shown a still further modified form of the invention. A cylinder 42 is supported by the shaft 43, journalled in the bearing 44, in an inclined position. The liquid 20 drips or flows on the cylinder from the pipe 45 and moves in a helical path upon the rotation of the cylinder toward the lower edge 46. The used liquid is collected in the vat 47 and led off through the pipe 48. A guide bar 49 is provided with 25 hooks 50 which maintain the thread 51 in a uniform helical path.

From the above description it will be appreciated that many changes may be made in the construction of the device without in any way 30 departing from the spirit or scope of the invention. Accordingly, the invention is to be limited, only by the scope of the following claims taken in view of the prior art.

The invention having been set forth as required by the patent statutes, what is claimed is:

- 35 1. In a device for treating continuous lengths of filaments of artificial origin, in combination, rollers arranged adjacent to one another, means to rotate said rollers, and means to supply treating liquid to one of said rollers, said supply means for treating liquid comprising a liquid supply means, and a means for forcing the liquid supplied along the face of the roll in a helical path.
- 40 2. In a device for treating continuous lengths of filaments of artificial origin, in combination, rollers arranged adjacent to one another, means to rotate said rollers, and means to supply treating liquid to one of said rollers, said supply means for treating liquid comprising a liquid supply means, and a means for forcing the liquid supplied along the face of the roller in a helical path, said last mentioned means consisting of a tube supply a stream of air under pressure at an angle tangential to the said roller.
- 45 3. In a device for treating continuous filaments of artificial origin, in combination, rollers arranged adjacent to one another, a means for supplying treating liquid at a series of spaced points on one of said rollers, and a means for spreading the liquid along said roller.
- 50 4. In a device for treating continuous filaments of artificial origin, in combination, rollers arranged adjacent to one another, a means for supplying treating liquid at a series of spaced points

on one of said rollers, and a means for spreading the liquid along said roller, said last named means comprising a blade-like strip arranged adjacent to the surface of the roller.

5. In a device for treating continuous filaments of artificial origin, in combination, rollers arranged adjacent to one another, a means for supplying treating liquid at a series of spaced points on one of said rollers, and a means for spreading the liquid along said roller, said last named means comprising a blade-like strip arranged adjacent to the surface of the roller and provided with a series of stops and openings at its edge adjacent said roller.

6. In a device for treating continuous lengths of formed filaments, in combination, a helically grooved rollers, means for guiding filaments thereover, and means for passing treating liquid through said grooves.

7. In a device for treating continuous lengths of formed filaments, in combination, a helically grooved roller, means for guiding filaments thereover, and means for passing treating liquid through said grooves, in a direction at an angle to the direction of movement of said filaments.

8. In combination, a pair of helically grooved rollers, around which the filaments are passed in a helical path, one of said rollers being at an angle to the other, and liquid passing through said grooves on said rollers, said treating liquid travelling in a path counter-current to the direction of travel of said filaments.

9. In a process for continuously producing artificial filaments, the steps of passing the filaments upwardly in a helical path around a rotating cylinder, and passing a treating fluid in a helical path at an opposed angle to the path of the filaments.

10. In a process of the type set forth, the step of passing a freshly formed artificial filament in a helical path over a rotating cylinder, and passing treating liquid over the said rotating cylinder at an opposed angle to the path of the filament.

11. In a device for continually treating filaments of artificial origin, in combination, a source of supply for treating liquid, means including a rotating roller for passing said treating liquid in a helical path around said roller, and means for guiding the filaments around said roller in a helical path at an angle to the path of the treating liquid.

12. In a device for continually treating filaments of artificial origin, in combination, a source of supply for treating liquid, means including a rotating roller for passing said treating liquid in a helical path around said roller, and means for guiding the filaments around said roller in a helical path at an opposed angle to the path of the treating liquid.
